UNITED STATES PATENT OFFICE.

JOHN W. CUNNINGHAM, OF TULSA, OKLAHOMA, ASSIGNOR TO CUNNINGHAM TANK PROTECTOR COMPANY, OF TULSA, OKLAHOMA, A CORPORATION OF OKLAHOMA.

OIL-TANK PROTECTOR.

1,159,831.

Specification of Letters Patent.

Patented Nov. 9, 1915.

Application filed November 5, 1914. Serial No. 870,477.

To all whom it may concern:

Be it known that I, JOHN W. CUNNINGHAM, a citizen of the United States, residing at Tulsa, in the county of Tulsa and State of Oklahoma, have invented certain new and useful Improvements in Oil-Tank Protectors, of which the following is a specification, reference being had to the accompanying drawings.

10 My invention relates to means for protecting tanks holding oil, gasoline or other inflammable liquids from danger of being set on fire by lightning.

15 It is a well known fact that lightning seldom strikes a tank containing gasoline or oil, but that in ninety per cent. of cases the lightning strikes and ignites the column of gas arising from the tank and floating upward into the air. The ignition of the 20 column of gas ignites the gas in the tank and the gas accumulated within the tank is exploded, thus igniting the oil or other liquid therein contained and rendering liable the ignition of other adjacent tanks.

25 The primary object of my invention is to obviate this danger by providing means whereby the gas may escape from the interior tank, this means, however, preventing the ignited gas from flowing back into the 30 tank and exploding the contents thereof.

A further object of the invention is to so construct the safety attachment which I have devised that the amount of opening through which the gas will pass out into the 35 atmosphere may be readily regulated and controlled.

A further object of the invention is to provide what may be termed a gas burner disposed at the vent opening of the tank, 40 permitting the outflow of inflammable vapors and permitting these inflammable vapors to burn exteriorly of the tank for preventing the passage of inflammable vapors into the interior of the tank.

5 Other objects will appear in the course of the following description.

My invention is illustrated in the accompanying drawings, wherein—

Figure 1 is a perspective view of a tank provided with my safety attachment at the vent opening; Fig. 2 is an enlarged perspective detail view of the attachment itself in place upon the tank; Fig. 3 is a fragmentary vertical section through the roof of said

tank and through the attachment. Figs. 4 and 5 are plan views of the disks 13 and 14.

Referring to these drawings, A designates an oil tank of the usual form having the upwardly inclined roof a, this roof being provided with a vent opening b. This tank 60 has any ordinary or usual form.

Disposed upon the top of the tank around the vent opening is a conical upwardly converging casing 2, which may be made of sheet metal or any other suitable material, 65 which is flanged at its bottom as at 3 and riveted, bolted or otherwise attached to the roof of the tank. The upper end of the conical casing 2 has an opening which is somewhat smaller than the opening b, and 70 riveted or otherwise attached to the upper end of the casing 2 is the upwardly extending cylindrical terminal cap 4 which has air inlet openings 5 in its side wall adjacent its lower end. The upper end of the cap is 75 formed with a plurality of perforations 6. Disposed within the cap 4 and arranged concentrically thereto is a cylindrical hood 7, the lower end of which is angularly flanged as at 8 for attachment to the lower end of 80 the cap 4. The hood 7 is of course smaller in diameter than the cap 4 and as a consequence is spaced from the cap so as to leave an annular passage 8 extending upward from the air openings 5 in the cap. The 85 hood 7 is shorter than the cap 4 and has a rounded upper end perforated as at 9. Disposed within this hood 7 is a conical valve 10 which is connected by means of any suitable connection 11 to a screw 12 which has screw 90 threaded engagement with the upper end of the cap 4. The valve 10 coacts with the opening 9, and by rotating the screw in one direction or the other the valve 10 may be raised or lowered so as to decrease or increase the area through which the gas passes from the interior of the head.

Disposed within the conical casing 2 are a plurality of metallic screens. Two screens are illustrated, one being designated 13 and 100 the other 14. These screens are formed with a plurality of small perforations 15, the perforations of one screen being disposed in staggered relation to the perforations on the next screen.

105 It will be obvious that a device of this character, while permitting the outward passage of gaseous vapors accumulated

within the interior of the tank, will prevent rain passing into the tank and will also prevent the passage into the tank of ignited gas, the aperture 9 in the hood 7 being relatively small and the apertures 15 in the baffle plates 13 and 14 being also relatively small. The size of the aperture 9 may of course be regulated by adjusting the valve 10 so that this aperture will be reduced or increased according to the exigencies of any particular case.

It will be noted that not only is the aperture 9 relatively small, and rendered smaller by the position of the apex of the conical valve therein, but the base of said valve has a diameter nearly equal to that of the hood, thus forming a relatively narrow annular passage around the base of the valve. It is also to be noted that the downwardly extending side wall of the casing 2 with the gradually larger baffle plates provide a series of chambers gradually increasing in diameter, so that the force of any explosion of gas in one chamber is lessened by the gas exploding in its passage into the next adjacent chamber, so that the force whereby the flame is blown through the perforations is very greatly lessened if the flame has reached the chamber between the plates 13 and 14.

It is also to be noted that the perforations 5 in the outer casing member 4 provide for an upward draft through the casing 4, and this upward draft acts to prevent the inlet of flame by urging the flame upward and away from the perforations 6, thus holding the flame at the top of the jacket or casing 4. The perforations in the baffle plates are small so that they act in snuffing out any flame that may reach them. The suction caused by the draft through the burners will have a tendency to create a vacuum between the baffle plates and cause the gas to be of such a mixture that it will be hard to ignite.

Having described my invention, what I claim is:

1. The combination with a tank for inflammable fluids and having a vent, of a protector for the vent including a hollow casing disposed over the vent and having a plurality of perforated baffle plates, the perforations being relatively small, the casing having a relatively small outlet perforation, and means in connection with the perforation for increasing or decreasing the amount of gas passing therethrough.

2. The combination with a tank for inflammable fluids, having a vent, of a protector for the vent comprising a hollow casing disposed over the vent, a hood disposed in the upper portion of the casing and having a relatively small outlet perforation, means in connection with the perforation for increasing or decreasing the amount of gas passing therethrough, and a plurality of apertured baffle plates disposed within said casing.

3. The combination with a tank for inflammable fluids, having a vent, of a protector for the vent comprising a hollow casing disposed over the vent, a cap formed on the upper end of the casing, a hood disposed within the cap and spaced from the wall thereof, said hood having a central outlet therefrom, and the cap over the upper end of the hood being formed with air inlets, and a plurality of perforated baffle plates disposed within the casing.

4. In a protector for oil tanks, a conical casing having a cylindrical upper extension, the upper end of the extension being open, a plurality of perforated baffle plates disposed within the casing, a hood mounted within the upper cylindrical extension and of smaller diameter than said extension, the upper end of the hood being formed with a central perforation, a conical valve disposed within the upper end of the hood and coacting with the perforation, a screw passing through the upper end of the cap, and a connection between said valve and screw.

5. In a protector for oil tanks, a conical casing having a cylindrical upper extension, the upper end of the extension being open, a plurality of perforated baffle plates disposed within the casing, a hood mounted within the upper cylindrical extension and of smaller diameter than said extension, the upper end of the hood being formed with a central perforation, a conical valve disposed within the upper end of the hood and coacting with the perforation, a screw passing through the upper end of the cap, and a connection between said valve and screw, the base of the conical valve having a diameter nearly equal to that of the hood.

In testimony whereof I hereunto affix my signature in the presence of two witnesses.

JOHN W. CUNNINGHAM.
